(57) **CLAIM**

The ornamental design for a propane tank cover as shown and described.

DESCRIPTION

FIG. 1 is a top, front, right side perspective view of a first embodiment of a propane tank cover showing our new design;

FIG. 2 is a bottom, back, left side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, back, left side perspective view of a second embodiment of the propane tank cover shown in FIG. 1;

FIG. 10 is a bottom, front, right side perspective view thereof;

FIG. 11 is a back elevational view thereof;

FIG. 12 is a front elevational view thereof;

FIG. 13 is a right side elevational view thereof;

FIG. 14 is a left side elevational view thereof;

FIG. 15 is a top plan view thereof; and,

FIG. 16 is a bottom plan view thereof.

The broken lines shown in FIGS. 8 and 16 illustrate portions of the propane tank cover that form no part of the claimed design.

1 Claim, 16 Drawing Sheets
